UNITED STATES PATENT OFFICE.

WILLIAM J. CAMMACK, OF LOS ANGELES, CALIFORNIA.

SIREN.

Application filed September 2, 1925, Serial No. 54,020. Renewed May 20, 1927.

My invention relates to sirens, and has among its salient objects to provide an improved and efficient siren adapted to be power operated, with means for connecting it with the power furnishing element with a minimum of apparatus and effort, and to provide means for stopping the siren by means of a brake action, with very simple and practical mechanism for setting said brake action.

Other features and advantages will appear from the following description of one practical embodiment of my invention, taken in connection with the accompanying sheet of drawings, in which,—

Figure 1 is a top plan view of a siren embodying my invention, partly in section;

Figure 2 is a front elevation thereof;

Figure 3 is an edge view of the siren element which makes the noise; and

Figure 4 is a side view showing the operating connections.

I will now describe in detail the invention as illustrated, or embodied, on the accompanying drawings. The invention is shown mounted on a cross member, 5, in front of the usual automobile radiator and slightly below, and the driving power is had from the engine shaft, 6, on which is mounted a driving element, 7, in the nature of a fly wheel, said shaft, 6, having an extension sleeve, 8, thereon, with spring, 9, therein, for use when it is necessary to crank the engine.

The siren includes a base or supporting casting, 10, secured to the cross member 5, by means of two U-bolts, 11, said supporting casting having a pivot bearing at 10' in which the siren proper is pivotally mounted, as will now be described.

The siren proper, as here embodied, comprises a tubular casting, 12, having the larger bell portion, 13, and having mounted therein a shaft, 14, with ball bearings at the opposite ends of said tubular member, 13, said bearings being designated, 15, 15. On the inner end of said shaft, 14, is a friction drive pulley or member, 16, positioned to be moved into and out of engagement with the periphery of the fly-wheel 7, in a manner hereinafter described. Said shaft is also provided on its inner end with a cup-like brake element, 17, adapted to be moved into and out of contact with a friction band, 18, fixedly mounted on the inside of the

tubular base or supporting casting, 10, as indicated.

On the outer end of the shaft 14, is mounted the siren fan or noise making element, 19, comprising a hollow wheel-like element 60 having a middle partition, 19^a, forming two chambers therein, designated, 19^b and 19^c, and with the edge wall provided with staggered openings, 19^d, as clearly indicated in the edge view thereof in Fig. 3. The inner 65 chamber, 19^b, is open around its center and in register with openings, 13^a in the bell casting 13, while the outer chamber 19^c is also open around its central portion, as at 19^e.

Mounted over said siren element 19, is an enclosure member, 20, of reduced diameter at its outer end, which is open, as at 21, while the larger portion of said member 20, is provided with openings, as 22 and 23, to 70 register with the openings, 19^d, from the two chambers, 19^b and 19^c.

A sound bell, as 24, is mounted on the bell casting 13, as indicated, and directs the currents of air forwardly, and also the tones 80 emanating from the revolving siren element 19, as will be understood.

The bell casting, 13, is connected by means of a rod, 25, to a rocker arm, 26, one arm of which is connected by means of a link, 27, 85 to a foot lever, 28, pivotally mounted, as at 29, whereby said foot lever can be rocked in either direction to push or pull on the link, 27, and thereby rock the rocker arm 26, and through the connecting rod 25, rock the 90 bell casting, 13, and the tubular casting 12, together with the shaft, 14, and its parts, on the pivot 10', in the base or supporting casting 10. When said parts are rocked in one direction, the friction drive pulley or 95 member 16 is moved into engagement with the driving element 7, whereupon said siren is power driven at high speed because of the relative diameters of the two frictionally engaged members. By rocking said parts in 100 the other direction, the brake cup, or member 17, is moved into frictional contact with the fixed brake band, 18, and brake action is at once applied to said revolving parts and they are stopped.

Air is drawn into said siren element from behind the bell casting 13, through its openings, 13^a, for the inner chamber 19^b, and from in front of the device, through the enclosure member 20, for the chamber 19^c of 110

the siren element 19. The air is forced out through the staggered openings, 19^a, in said element, and out through the openings, 22 and 23, in said enclosure member, 20, and 5 out through the bell member 24, and forwardly, as will be clearly understood with the showing made.

Thus I have provided a practical means for operating the siren and for applying a 10 brake action thereto, when it is desired to stop it. The tones produced by the siren will depend upon the chambers 19^b and 19^c and the quantity of air forced therethrough.

While I have shown and described in detail 15 one form or embodiment of my invention, I am aware that changes can be made in the details thereof without departing from the spirit of the invention, and I do not, therefore, limit my invention to the 20 showing made, except as I may be limited by the hereto appended claims.

I claim:

1. In a siren, in combination, a base, a 25 driving element with means for driving the same, a siren element revolvably mounted in said base and adapted to be driven from said driving element, said siren element having a part adapted to be moved into and out of engagement with said driving element, a brake element fixedly mounted on 30 said base, and a part on said siren element adapted to be moved into and out of engagement with said brake element, whereby to stop the revolving movement of said siren element.

2. In a siren, in combination with a driving element and means for driving the same, of a siren element revolvably mounted, means 40 pivotally supporting said siren element to permit its rocking movement, a part on said siren element adapted to be moved into and out of driving engagement with said driving element as said siren element is rocked upon its support, a fixed brake element, a 45 part on said siren element adapted to be moved into and out of engagement with said

brake element as said siren element is rocked upon its support, and means for rocking said siren element at will to cause its operation or to stop its operation.

3. In a siren, in combination with a driving member, a movable supporting member, a siren revolvably mounted in said supporting member, said siren having a part adapted to be moved into and out of engagement with said driving member, said siren also having a body with two chambers partitioned from each other, said chambers having inlet openings near their central portions through their outer walls and outlet openings in their outer edge walls, whereby air is drawn into said siren from opposite directions and on opposite sides of the partition and thrown out through the edge walls, means for moving said supporting member to put said part into driving engagement with said driving member, and a brake member adapted to operate on said siren to stop the same when said movable supporting member is moved in one direction.

4. In a siren, a base casting having a 70 brake element fixedly positioned thereon, a siren casting movably connected to said base casting and having a bell portion at its outer end, a siren body having two chambers 75 therein with inlet openings from opposite sides, centrally thereof, and with outlet openings through their outer edge walls within said bell portion of said siren casting, a driving shaft for said siren body extended into said siren casting and having a brake element thereon adjacent the brake element on said base casting, means for moving said shaft brake element into engagement with said fixed brake element, and 80 a driving element on said shaft for driving said siren body.

Signed at Los Angeles, Los Angeles County, California, this 26th day of August, 1925.

WILLIAM J. CAMMACK.
